UNITED STATES PATENT OFFICE.

PAUL S. BOSTWICK, OF WOODBINE, IOWA.

STEAM-ENGINE.

SPECIFICATION forming part of Letters Patent No. 729,997, dated June 2, 1903.

Application filed May 5, 1902, Serial No. 105,983. (No model.)

To all whom it may concern:

Be it known that I, PAUL S. BOSTWICK, a citizen of the United States, and a resident of Woodbine, in the county of Harrison and State of Iowa, have invented a new and Improved Steam-Engine, of which the following is a full, clear, and exact description.

The object of the invention is to provide a new and improved steam-engine which is simple and durable in construction, very effective in operation, easily reversed, and arranged to utilize the power developed in the cylinder to the fullest advantage in transmitting the power to the main shaft without producing dead-center positions and dispensing entirely with the use of a pitman and crank on the main shaft.

The invention consists of certain parts and details and combinations of the same, as will be fully described hereinafter and then pointed out in the claims.

A practical embodiment of my invention is represented in the accompanying drawings, in which similar characters of reference indicate corresponding parts in all the figures.

Figure 1 is a side elevation of the improvement. Fig. 2 is a plan view of the same. Fig. 3 is an enlarged longitudinal sectional elevation of the main cylinder, the holding mechanism for the endless transmission-belt, and the actuating device for the holding mechanism. Fig. 4 is a sectional plan view of the actuating device for the holding mechanism, the section being taken on the line 4-4 of Fig. 3. Fig. 5 is a transverse section of the same on the line 5-5 of Fig. 4. Fig. 6 is a similar view of the same with the parts in a different position. Fig. 7 is an end view of the cross-head and the holding device for the endless belt, the latter being shown in section. Fig. 8 is a sectional side elevation of a modified form of the holding device for the endless belt, and Fig. 9 is an inverted sectional plan view of the same on the line 9-9 of Fig. 8.

The engine is mounted on a suitably-constructed frame A, supporting the main cylinder B, having cylinder-ports *a* and *b* leading to the steam-chest C, containing the usual valve, (not shown,) actuated from the main shaft D of the engine by a suitable mechanism, such as an eccentric E or the like, to con-

trol the admission and exhaust of the motive agent to and from the cylinder B in the usual manner.

In the main cylinder B reciprocates the main piston F, having a piston-rod G, connected with the cross-head H, mounted to slide in bearings H', carried by the main frame A, and on the said cross-head H are arranged holding devices I and I' for alternately engaging the runs of an endless belt, rope, or cable J, passing over a drum or double pulley K, secured on the main shaft D. The endless belt J also passes over idlers L and L', of which the idler L is held adjustably on the main frame A (see Figs. 1 and 2) to give the desired tension to the endless belt J to prevent the latter from slipping on the drum or double pulley K. The other idler L' is journaled at the outer end of the main cylinder B and is arranged to direct the runs of the belt J between the sides of the cross-head H for the runs to be alternately engaged by the holding devices I and I' to impart a continuous traveling motion to said endless belt when the engine is running, as hereinafter more fully described. Guide-rollers L², journaled on the main frame A, guide the runs of the belt J to and between the sides of the cross-head H at the forward end of the engine.

The holding devices I and I' are actuated by the motive agent passing into the main cylinder B, and for this purpose the following device is provided: The main piston-rod G is formed with longitudinally-extending channels *c* *d*, opening into the cylinder B at opposite sides of the piston F, (see Fig. 3,) and the outer ends of said channels *c* and *d* open into the valve-casing N' of a valve N for controlling the admission of the motive agent to an auxiliary cylinder O, containing an auxiliary piston P, having its piston-rod P' extending in the cross-head H, said valve-casing N' and cylinder O forming a connecting portion between the main piston-rod G and the cross-head H, as will be readily understood by reference to Fig. 3. The valve-casing N' is connected by cylinder-ports *e* and *f* with the ends of the cylinder O, as is plainly indicated in Fig. 4, so that the steam passes into said cylinder to impart a reciprocating motion to the piston P and its pis-

ton-rod P' whenever the main piston reaches the ends of its stroke. On the auxiliary piston-rod P' is secured a cross-head Q, connected by links Q' and Q² with levers R R', fulcrumed on the cross-head H, the lever R being connected by links R² R³ with sets of jaws I² I³, fulcrumed on the cross-head H and adapted to engage and disengage the upper run of the endless belt J. The other lever, R', is pivotally connected by the links R⁴ R⁵ with a set of jaws I⁴ and I⁵, likewise fulcrumed on the cross-head H and adapted to engage and disengage the lower run of the endless belt J as the latter passes through the cross-head H. Now by reference to Fig. 3 it will be seen that when the auxiliary piston P moves in one direction the set of jaws I² I³ is moved in clamping engagement with the upper run J, while at the same time the set of clamping-jaws I⁴ I⁵ is moved out of engagement with the lower run of the belt J, and as the cross-head H now travels in the direction of the arrow a' it is evident that the upper run of the endless belt J is moved in the same direction, while the lower run of the endless belt passes loosely through the said cross-head and the jaws I⁴ I⁵. When the motion of the auxiliary piston P is reversed, the jaws I⁴ I⁵ engage the lower run of the endless belt J, so as to lock this run to the cross-head H, while at the same time the jaws I² I³ move out of engagement with the upper run of the belt J, and as at this time the cross-head H moves in the inverse direction of the arrow a' it is evident that another impulse is given to the endless belt J by the jaws I⁴ I⁵ locking the lower run of the belt to the cross-head H. When the several parts are in the position illustrated in Figs. 3, 4, and 5, the main piston F is on the outward stroke—that is, in the direction of the arrow a'—and the steam passing into the inner end of the cylinder B to move said main piston F in the outward direction also passes through the channel b into the valve-casing N' and by way of the valve N is directed to the port f to pass into the cylinder O and to press the auxiliary piston P likewise in the direction of the arrow a' to hold the jaws I² I³ in gripping engagement with the upper run of the belt J and to hold the jaws I⁴ I⁵ out of engagement with the lower run of the endless belt J. Now when the main piston F reaches the end of its outward stroke and steam passes into the cylinder B through the port a to press the piston F on the return stroke—that is, in the inverse direction of the arrow a'—then part of this steam passes through the channel c, the valve N, and the port e into the cylinder O to push the piston P in the inverse direction of the arrow a' and cause the jaws I² I³ to release the upper run of the endless belt J and also to cause the jaws I⁴ I⁵ to grip the lower run of the endless belt, and thus lock this lower run to the cross-head H. As the cross-head H moves in unison with the piston F and the holding devices I and I' are

alternately actuated to lock the runs of the endless belt J alternately to the cross-head H, it is evident that a continuous traveling motion is given to the endless belt J to rotate the drum or pulley K in one direction, thus rotating the main shaft D.

The valve N is preferably made cylindrical and extends in about the middle portion of the valve-casing N', and in the peripheral face of said valve are formed ports g, h, and i, opening alternately into the valve-casing N' at opposite sides of the valve N, as will be readily understood by reference to Figs. 4, 5, and 6. When the several parts are in the positions shown in Figs. 3, 4, and 5, then the port g is in register with the channel d to conduct the live steam from the channel d through the port g into the end of the valve-casing N', connected with the port f, so that the steam can pass into the cylinder O at the forward end to press the piston P in the direction of the arrow a'. The exhaust on the other side of the piston P now takes place through the cylinder O, the port e, and the valve-casing N', and the port h registers with the channel c, leading to the exhaust end of the cylinder B. Now the motive agent passes into the outer end of the cylinder B by way of the port a, a portion of the motive agent passing through the channel c and the port h into the valve-casing N' and through the port e into the cylinder O to move the piston P in the reverse direction, the exhaust on the other side of the piston now taking place through the port f, the casing N', the port g, and the channel d, opening into the exhaust end of the cylinder B.

When it is desired to reverse the engine, the valve N is turned so as to bring the port h into register with the channel d and the port i into register with the channel c to cause the live motive agent to travel in the reverse direction from the cylinder B into the auxiliary cylinder O and to cause the piston P therein to move in the reverse direction to the piston F, so that the holding devices I' and I are alternately actuated to clamp and release the lower and upper runs of the endless belt J alternately to cause said belt to travel in the inverse direction of the arrow a'. The valve N is provided with heads N³ and N⁴ to prevent leakage of the steam. (See Figs. 4, 5, and 6.) In order to impart the desired reversing motion to the valve N, I provide one outer end of the valve-stem N² with a crank-arm S, having its wrist-pin S' engaging a longitudinally-extending guideway T, hung on the bell-crank levers U U', pivotally connected with each other by a link U², connected by a link U³ with a reversing-lever V, having the usual locking device V' for locking the reversing-lever in the desired position on the arched segment V². Now when it is desired to turn the valve N for reversing the engine, as described, it is only necessary for the operator to swing the reversing-lever V over so as to move the guideway T down-

ward, and thereby impart a swinging motion to the crank-arm S to turn the valve N into the position shown in Fig. 6. When the valve reaches this position, the port g is moved out of engagement with the channel d and the port h is moved in register with the channel d and the port i is moved in register with the channel c.

I do not limit myself to the particular construction of holding device employed for locking the runs of the endless belt alternately to the reciprocating cross-head H, as said holding device may be varied. For instance, as shown in Figs. 8 and 9, I dispense with the clamping-jaws and employ brake-wheels and brake-bands for the same purpose. In the construction shown in Figs. 8 and 9 I provide the auxiliary piston-rod P' with a cross-head Q³, connected at each end by a link Q⁴ with a lever W, on which are pivoted the ends of the brake-bands W' W², extending in opposite directions and winding on the brake-wheels W³ W⁴, journaled in suitable bearings carried on the cross-head H. On the brake-wheels W³ W⁴ are formed or secured double pulleys W⁵ W⁶, over which passes a run of the endless belt J', the said run also passing over guide-rollers L⁴, traveling on the cross-head H. Now when the piston moves in one direction the brake-bands W' W² of one holding device are drawn in braking contact with the two wheels W³ W⁴ to hold the pulleys W⁵ W⁶ against rotation, so that the corresponding run of the endless belt J' is locked to the cross-head H, while the other run is free to travel over the pulleys W⁵ W⁶, left free to rotate, as their brake-wheels W³ W⁴ are not engaged by the corresponding brake-bands W' W².

Having thus described my invention, I claim as new and desire to secure by Letters Patent—

1. A steam-engine comprising a cylinder, a piston reciprocating therein, a cross-head connected with the piston, an endless belt, a main shaft carrying a pulley over which passes the belt, idlers over which passes the belt, holding devices on the said cross-head for alternately holding the runs of the belt to the cross-head, an auxiliary cylinder and a piston therein and actuating the holding devices in unison with the main piston, as set forth.

2. A steam-engine comprising a cylinder, a piston reciprocating therein, an endless belt, a cross-head through which pass the runs of said belt, the cross-head being connected with the piston-rod of said piston, a main shaft carrying a pulley over which pass the belt, holding devices on said cross-head for alternately clamping the runs of the belt to the cross-head, an auxiliary cylinder, a piston therein, and means controlled by the piston of the auxiliary cylinder for opening one holding device while closing the other, as set forth.

3. A steam-engine comprising a main cylinder, a main piston reciprocating therein, a cross-head carried by the piston-rod of said

main piston, an endless belt extending with its runs through said cross-head, a main shaft carrying a pulley over which pass the belt, holding devices on the cross-head for alternately locking the runs of the belt to the cross-head, an auxiliary cylinder on the piston-rod, an auxiliary piston in the said auxiliary cylinder and having its piston-rod connected with the holding devices to open one while closing the other, and a valve for controlling the admission and exhaust of the motive agent to and from the auxiliary cylinder, as set forth.

4. A steam-engine comprising a main cylinder, a main piston reciprocating therein, a cross-head carried by the piston-rod of said main piston, an endless belt extending with its runs through said cross-head, a main shaft carrying a pulley over which pass the belt, holding devices on the cross-head for alternately locking the runs of the belt to the cross-head, an auxiliary cylinder on the piston-rod, an auxiliary piston in the said auxiliary cylinder and having its piston-rod connected with the holding devices to open one while closing the other, a valve for controlling the admission and exhaust of the motive agent to and from the auxiliary cylinder, and manually-controlled means for reversing said valve, as set forth.

5. A steam-engine comprising a main cylinder, a main piston reciprocating therein, a cross-head carried by the piston-rod of said main piston, an endless belt extending with its runs through said cross-head, a main shaft carrying a pulley over which pass the belt, holding devices on the cross-head for alternately locking the runs of the belt to the cross-head, an auxiliary cylinder on the piston-rod, an auxiliary piston in the said auxiliary cylinder and having its piston-rod connected with the holding devices to open one while closing the other, and a valve for controlling the admission and exhaust of the motive agent to and from the auxiliary cylinder, said main cylinder being connected by channels in the main piston-rod with the said valve, as set forth.

6. An engine provided with a main cylinder, a main piston reciprocating therein and having a main piston-rod provided with longitudinal channels opening into the main cylinder at opposite sides of the piston, an auxiliary cylinder on the main piston-rod, an auxiliary piston therein and connected with a holding device for actuating the same, and a valve on the main piston-rod for controlling the admission and exhaust of the motive agent to and from the auxiliary cylinder by way of said channels, as set forth.

7. An engine provided with a holding mechanism for an endless belt, and an actuating device for said holding mechanism and comprising an auxiliary cylinder, an auxiliary piston reciprocating therein, and a valve for controlling the passage of the motive agent to and from said auxiliary cylinder, as set forth.

8. An engine provided with a holding mechanism for an endless belt, an actuating device for said holding mechanism and comprising an auxiliary cylinder, an auxiliary piston reciprocating therein, a valve for controlling the passage of the motive agent to and from said auxiliary cylinder, a crank-arm on said valve, a guide for said crank-arm, and a reversing-lever connected with said guide, as set forth.

9. An engine having an endless belt, a cross-head reciprocating in the direction of the length of the runs of the belt, a holding device carried by the cross-head and adapted to alternately lock the cross-head to the runs of the belt, the holding device comprising two sets of jaws, one for each run of the belt, levers and links connected with the jaws for opening and closing the same, and a cylinder moving in unison with the cross-head and having a piston connected by its piston-rod with said levers, as set forth.

10. An engine having an endless belt, a cross-head reciprocating in the direction of the length of the runs of the belt, a holding device carried by the cross-head and adapted to alternately lock the cross-head to the runs of the belt, the holding device comprising two sets of jaws, one for each run of the belt, levers and links connected with the jaws for opening and closing the same, and a cylinder moving in unison with the cross-head and having a piston connected by its piston-rod with said levers, said cylinder receiving its motive-agent supply from the main cylinder of the engine, as set forth.

11. An engine having an endless belt, a cross-head reciprocating in the direction of the length of the runs of the belt, a holding device carried by the cross-head and adapted to alternately lock the cross-head to the runs of the belt, the holding device comprising two sets of jaws, one for each run of the belt, levers and links connected with the jaws for opening and closing the same, a cylinder moving in unison with the cross-head and having a piston connected by its piston-rod with said levers, said cylinder receiving its motive-agent supply from the main cylinder of the engine, and a valve for controlling the admission and exhaust of the motive agent to and from the auxiliary cylinder from and to the said main cylinder, as set forth.

12. An engine having an endless belt, a cross-head reciprocating in the direction of the length of the runs of the belt, a holding device carried by the cross-head and adapted to alternately lock the cross-head to the runs of the belt, the holding device comprising two sets of jaws, one for each run of the belt, le-

vers and links connected with the jaws for opening and closing the same, a cylinder moving in unison with the cross-head and having a piston connected by its piston-rod with said levers, said cylinder receiving its motive-agent supply from the main cylinder of the engine, a valve for controlling the admission and exhaust of the motive agent to and from the auxiliary cylinder from and to the said main cylinder, and means for reversing said valve, as set forth.

13. In an engine, a main cylinder, a piston therein and provided in its rod with longitudinal ports opening on opposite sides of the piston, a cross-head, a valve-chamber to which the piston-rod is connected, an auxiliary cylinder secured to the cross-head and valve-chamber, a piston in said auxiliary cylinder, a cable, holding devices for the cable, and a connection between the holding devices and 80 piston of the auxiliary cylinder, as set forth.

14. In an engine, a main cylinder, a piston therein and provided in its rod with longitudinal ports opening on opposite sides of the piston, a cross-head, a valve-chamber to which the piston is secured, an auxiliary cylinder connecting the valve-chamber with the cross-head, a piston in the auxiliary cylinder, a valve in the valve-chamber, a cable, holding devices for the cable, and a connection between the holding devices and the piston of the auxiliary cylinder, as set forth.

15. In an engine, a cylinder, a piston therein, an endless belt, a main shaft carrying a pulley over which passes the belt, pivoted levers, sets of jaws, links connecting the levers with the jaws, an auxiliary cylinder, a piston in said cylinder and connected with said levers, and means for controlling the admission of the motive agent from the main cylinder to 100 the auxiliary cylinder, as set forth.

16. In an engine, a cylinder, a piston therein, a cross-head, an endless belt, a main shaft carrying a pulley over which passes the belt, pivoted levers mounted on the cross-head, sets of jaws, links connecting the jaws with the levers, an auxiliary cylinder, a piston therein, a connection between the piston-rod of the piston of the auxiliary cylinder and the said levers, and means for controlling the admission of the motive agent from the main cylinder to the auxiliary cylinder, as set forth.

In testimony whereof I have signed my name to this specification in the presence of two subscribing witnesses.
